UNITED STATES PATENT OFFICE.

GABOR HATVANY, OF NEWELL, PENNSYLVANIA.

BOTTLE.

1,147,629.

Specification of Letters Patent. Patented July 20, 1915.

Application filed February 18, 1914, Serial No. 819,574. Renewed June 18, 1915. Serial No. 34,959.

To all whom it may concern:

Be it known that I, GABOR HATVANY, a subject of the King of Hungary, residing at Newell, in the county of Fayette and State 5 of Pennsylvania, have invented certain new and useful Improvements in Bottles, of which the following is a specification, reference being had therein to the accompanying drawing.

10 This invention relates to bottles, and the object of my invention is to provide a bottle with top and bottom openings, said openings being in the form of necks with the neck in the bottom of the bottle housed by 15 the bottle whereby it is concealed and cannot be accidentally broken or interfere with the use of the bottle in the ordinary manner. The neck at the top of the bottle is shaped to accommodate a metallic closure that can be 20 sealed whereby it cannot be opened except by resorting to special implements.

The bottle will be hereinafter specifically described and then claimed, and reference will now be had to the drawing, wherein:— 25 Figure 1 is a vertical sectional view of the bottle, and Fig. 2 is a horizontal sectional view of the same.

In the drawing the reference numeral 1 denotes a bottle body having a breast 2 30 provided with a neck 3 and the upper edges of the neck are provided with an annular depending rim 4. Fitted in the neck 3 is a stopper 5 having an annular malleable cap 6 adapted to have the edges 7 thereof bent 35 under the rim 4 to prevent the cap and stopper from becoming accidentally displaced. A special implement, forming no

part of this invention, can be used for securing the cap to the rim of the neck.

The body of the bottle has a heavy or 40 thick bottom 8 provided with a conical-shaped recess 9 and within said recess is a depending neck 10 that is in communication with the interior of the bottle. The neck 10 is formed integral with the bottom 8 and 45 said neck accommodates a stopper 11 having a cup-shaped gasket 12 made of rubber or other yieldable material.

After the bottle has been opened in the usual manner and completely emptied the 50 stopper 11 can be removed and thrown away, thereby preventing the bottle from being used again in its original form, as the use of another stopper in the neck can be readily detected. 55

What I claim is:—

A bottle comprising a body portion 60 formed with a neck provided with an annular rim, a stopper arranged within said neck, a malleable cap carried by said stopper and having the edges bent under the rim, the bottom of said bottle being formed of a conical-shaped recess and a neck integral with the bottom projecting into said recess and in communication with the interior of said bottle, and a stopper detachably mounted in said last mentioned neck. 65

In testimony whereof I affix my signature in the presence of two witnesses.

GABOR HATVANY.
